Attorney

UNITED STATES PATENT OFFICE.

DANIEL GORDON, OF NEW YORK, N. Y.

INCANDESCENT LAMP.

Application filed October 23, 1919. Serial No. 332,595.

To all whom it may concern:

Be it known that I, DANIEL GORDON, a citizen of the United States, residing at New York, in the county of New York and State 5 of New York, have invented certain new and useful Improvements in Incandescent Lamps; and I do declare the following to be a full, clear, and exact description of the invention, such as will enable others skilled in 10 the art to which it appertains to make and use the same.

This invention relates to improvements in incandescent lamps.

The primary object is to provide a simple 15 and practical lamp provided with two filaments so constructed that should one of said filaments burn out the second filament will be automatically lighted without the least delay.

20 With the above and other objects in view, the invention consists of certain novel features of construction and the combination and arrangement of parts as will be more fully described and claimed.

25 I attain these objects by constructing the lamp as illustrated in the accompanying drawings, in which—

Fig. 1 is a vertical sectional view showing the first circuit broken and the second 30 or emergency circuit in use, and

Fig. 2, is a similar view, but showing the first circuit in use.

Similar numerals of reference designate 35 similar parts throughout the views.

Reference is now had to the drawing in which is shown a bulb 1 of the usual construction. Mounted upon one end of the bulb is the usual socket engaging plug 2 that embodies a shell 3 having one end 40 rounding the neck of the bulb and fastened thereto, and the other end equipped with a block 4 of insulating material carrying a contact 5, the latter and the shell 3 being adapted to engage the respective central 45 contact and shell of the socket or receptacle that is connected in the electric circuit. Extending into the butt end of the bulb 1 is a short glass tube 6 formed with a closed inner end and with an open rear end to receive a block to be described. As is readily seen, the tube is formed integral with the bulb. Extending from the inner end of the 50 short tube 6 is an elongated glass stem 7 provided at its outer end with inner and

outer sets of radiating arms 8 and 9 respectively, adapted to support two separate filament circuits 10 and 11.

Mounted in said tube 6 is a block 12 of suitable insulating material adapted to support an electromagnet 13 which is in circuit 60 with the filament 11 as shown. The block is provided in its inner face with a socket 14, to one wall of which one end of the filament is attached. Extending inwardly from the bottom of the socket is a suitable spring arm 65 or switch arm 15, which, when the bulb is lighted, is attracted by the magnet to open the filament circuit 10. The end of the circuit 10 is provided with a contact point 16 shown in the drawing as being a small angular piece of metal.

A short wire 17 connects the inner end of the switch arm 15 to the shell of the socket engaging plug 2 so as to complete the circuit 75 when the filament 11 is broken. The other ends of the filament circuits are suitably connected to the contact 5 as shown.

In operation, the bulb is placed in a socket and for an instant both filaments are lighted, but the action of the energized electromagnet 13 attracts the switch arm 15 and opens the filament circuit 10 and leaving the filament 11 burning. Should the filament circuit become broken, the switch arm is released and closes the filament circuit 10. It 85 is readily seen that this construction doubles the life of an incandescent lamp and is operable automatically when one filament is broken.

From the foregoing description taken in 90 connection with the accompanying drawings, the construction and operation of the invention will be understood without requiring a more extended explanation.

Various changes in the form, proportion 95 and minor details of construction may be resorted to, without departing from the principle or sacrificing any of the advantages of the claimed invention.

I claim:

In an incandescent lamp, a bulb having a pocket extending inwardly from its butt end and having its inner end closed, an insulating block in said pocket, a shell plug having the butt end portion of the bulb fitting therein, an insulating block carried by the plug, a terminal contact carried by the plug block, a normally closed switch carried

100

105

by the bulb block in the pocket, a filament wire leading from the terminal contact and connected with the shell plug and having the electro-magnet in its circuit and energizing the electro-magnet to open the switch. 10
6 included in its circuit, an electromagnet carried by the bulb block adjacent the switch, and a second filament wire leading from the terminal contact and connected with the shell plug and having the electro-magnet in its circuit and energizing the electro-magnet to open the switch.

In testimony whereof I have hereunto set my hand.

DANIEL GORDON.
